UNITED STATES PATENT OFFICE.

CHARLES J. WANGLER, OF ST. LOUIS, MISSOURI.

BOILER-MAKER'S SPACER.

SPECIFICATION forming part of Letters Patent No. 663,053, dated December 4, 1900.

Application filed August 30, 1900. Serial No. 28,563. (No model.)

To all whom it may concern:

Be it known that I, CHARLES J. WANGLER, a citizen of the United States, residing at the city of St. Louis, State of Missouri, have invented a new and useful Improvement in Boiler - Makers' Layer - Outs or Spacers, of which the following is a specification.

My invention relates to an improvement in devices intended for use in laying out or dividing and space-marking lines to be punched for the insertion of rivets and the like in sheet metal, such as boiler-iron, steel, and similar material; and the object of my invention is to afford a simple and reliable mode of dividing and spacing such lines or material required to be punched into any given number of equal parts, and thereby enable the workman to dispense with a tedious process of measuring between points with a compass or dividers, thus saving time and labor. I attain this object by the device shown in the accompanying drawings, in which—

Figure I is an illustration of my spacer, showing it inclined in a position for its minimum spacing. Fig. II is a similar perspective of the same, showing it in a position the reverse of Fig. I for its maximum spacing; and Fig. III is an illustration of the same, showing it with its members at right angles to each other in a position for its medium scope for a space-marking. The dotted lines in this figure illustrate its position in use upon the sheet metal to be marked. Figs. IV and V are cross-sectional views on lines 4 and 5, Fig. 35 II, respectively, showing its connections and a mode of fastening, as desired.

In the drawings similar letters and figures refer to similar parts throughout the same.

My device thus illustrated consists of a frame A, comprising two parallel longitudinal parts 1 and 2, between and to which are pivoted at regular intervals of space three or more lateral or connecting parts 3 3 3, provided with holes 7 7 at the ends of each, where 45 they are movably affixed by the hole-and-pin connections 4 4, 4' 4', and 8 to the parallel parts 1 and 2 in such a manner as permits of either a right or left hand movement and adjustment of the frame A, in which movements the

connecting parts 3 3 3 are placed at right angles to or inclined toward each other on a line or lines running diagonal or at right angles to the parallel connecting parts 1 and 2, which thus approach or recede from each other, as the operator may desire. As a material for 50 the frame I use sheet iron or steel strips, although it is obvious that other materials may be thus employed. In the frame A thus constituted and operating I then draw a line across it upon the flat faces of the connecting 55 parts 3 3 3, between the parallel parts 1 and 2, it being essential that said line should run diagonal to said parallel parts 1 and 2 either upwardly from right to left or downwardly from right to left. I have shown the result 60 of using but one of such lines in the drawings, as that is sufficient to illustrate the object and purposes of my invention. Upon the diagonal line thus drawn and where the same intersects the center of the width of each 65 of the connecting parts 3 3 3 said connecting parts or as many of them as may be desired more than three are punched or provided with a hole x x x, through which the material to be space-marked is thus marked with a pen- 70 or otherwise.

To retain the frame A fixed in any desired spacing-points distance, I provide a clamp or thumb-screw 5 5, Fig. V, by extending one or more of the pivot-pins 8 and threading it, 80 so as to receive and operate the thumb nut or nuts 6 6; but other well-known means may be employed for that purpose.

Having thus described my invention, that which I claim as new, and desire to secure by 85 Letters Patent, is—

1. In a boiler-maker's layer-out, or spacer, the movable pivotally-connected frame having two parallel longitudinal parts, to which three or more connecting parts are equally 90 spaced and movably attached near their ends and provided with holes or openings that run across the frame on a line diagonal to the parallel longitudinal parts, substantially in the manner shown and described and for the purposes set forth.

2. In a boiler-maker's layer-out, or spacer, the movable pivotally-connected frame hav-

ing two parallel longitudinal parts, to which three or more connecting parts are equally spaced and movably attached near their ends and provided with holes or openings that run across the frame on a line diagonal to the parallel longitudinal parts in combination with one or more clamps, all substantially in the

manner shown and described and for the purposes specified.

CHAS. J. WANGLER.

In presence of—

D. B. MCFARLAND,
R. M. FLETCHER.
